UNITED STATES PATENT OFFICE.

NIC KRUMP, OF CHICAGO, ILLINOIS.

SAFETY-SWITCH FOR A SUSPENDED TWO-RAIL TRACK.

1,389,668.

Specification of Letters Patent.

Patented Sept. 6, 1921.

Application filed January 28, 1921. Serial No. 440,595.

To all whom it may concern:

Be it known that I, NIC KRUMP, a citizen of the United States, a resident of Chicago, county of Cook, and State of Illinois, have 5 invented certain new and useful Improvements in a Safety-Switch for a Suspended Two-Rail Track, of which the following, reference being had to the drawings accompanying and forming a part hereof, is a 10 specification.

This invention relates to a switch for a two-rail suspended track system, such as is 15 usable in machine and other shops, factories and similar places, for transporting raw, finished and other material about said factories, etc.

Among the objects of this invention is to obtain a switch which is adapted to support heavy loads, to present smooth track ways 20 over which carriages having flanged wheels adapted to travel on a suspended two rail track may travel without noticeable jar; to obtain a switch of the kind named which is easily operated and not liable to get out of 25 order; and a switch which will not permit a carriage suitable to travel thereover, to run off therefrom when the switch is not set to make a continuous line for said carriage.

In the drawings referred to—

30 Figure 1 is a top plan view of a switch embodying the invention.

Fig. 2 is a vertical section of the switch.

Fig. 3 is a horizontal section on line 3—3 of Fig. 2 viewed in the direction indicated 35 by arrows, and

Fig. 4 is a section on line 4—4 of Fig. 2 viewed in the direction indicated by arrows.

A reference character applied to designate 40 a given part indicates said part throughout the several figures of the drawing wherever the same appears.

X represents a longitudinally extending beam to which the track and switch about to be described are suspended.

45 A represents the member supporting the pivotal end of the switch illustrated and the ends of the rails (BB) which extend to said pivotal end of the switch.

The member A comprises the web member 50 or base α which is illustrated, in Fig. 2, as rigidly secured to the beam X by bolts C. C. Said member A also comprises a supporting member α^1 and a vertical web α^2 joining said members α α^1 and integral therewith.

55 D represents a chair member which is rig-

idly secured to part α^1 of member A by bolts d d . The ends of rails B B rest on chair member D and are rigidly secured thereto.

E represents the bolt which forms a pivot 60 on which the switch turns and F represents a body member forming one end of the switch which rests on the table formed by parts α^1 of member A (see Fig. 2) and through which the bolt E extends. G represents a 65 chair member similar to member D which is secured to member F by bolts g g .

H represents rail members of the switch. I represents members by means of which the rails B and H are secured in the chair members D and H. 70

J J represent angle iron members which are secured at one end to member A by bolts j j and at the other end to member K by bolts j^1 j^1 . 75

The members A J K form a triangular rigid construction which may be termed the base of the movable rail carrying members of the switch.

Member K is rigidly secured in place by 80 bolts k k to a suspending beam, as X, and said member K is provided with a rail member; (L), on which rail the roller M of the about to be described movable end of the switch travels, as the switch is operated. 85

N represents a traveling member, comprising the head n in which the axle O is secured and on which axle the pulley P is rotatably mounted to travel on track L. The lower end n^1 supports the chair member Q, said chair member being rigidly secured thereto by bolt q . 90

The member K hereinbefore referred to supports the several chair members Q ^{1} Q ^{1} Q ^{1} which are secured to said member K by bolts 95 q^1 q^1 . One end of the switch rails H H is secured in the chair member Q and the end of the several rails R R which extend from the switch are secured in chair Q ^{1} .

S S represent the safety arms or bars of 100 the switch which are fulcrumed on pivots T T so that the free ends thereof rest on rails R R of the several tracks leading from the switch when the switch is not adjusted to receive a carriage from said rails or discharge one thereonto, so that the normal position of said safety members is with the free ends thereof resting on said rails. 105

S ^{1} represents an abutment on member S adjacent to the fulcrum of said lever and T. 110

represents a longitudinally movable bolt which is loosely mounted in member K. V represents a cam member which is illustrated as integral with the vertical portion of traveling member N.

W represents a cable by means of which traveling member N is moved to the right or left as required. W¹ represents a bolt which is yieldingly held in an advanced position by 10 spring W² and W³ W³, Figs. 1 and 2, represent recesses on the side of track member L in which recesses the forward end of bolt W¹ is yieldingly held by spring W². The entering of said end of said bolt into said recess 15 advises the person operating cable W that the switch is properly "set."

To operate the switch it is merely necessary to manipulate cable W to move traveling member N, to the right or left (pulley P 20 traveling on rail L), until the bolt W¹ advises the operator that traveling member N is in proper position. At this time the safety members S S of the rails R R, to which the switch is "set" are raised by 25 means of cam V and longitudinally movable bolt U, into the position illustrated by full lines in Fig. 2 and the carriage on the switch (rails H) may travel to rails R R, or vice versa, underneath said safety members S S. 30 Where, as illustrated in Fig. 1, there are three tracks of double rails extending from one end of the switch, as the traveling member N is "set" for a given one of said tracks, the safety members S S which pertain to a given track is raised from and dropped back to the position indicated by broken lines in Fig. 1 as traveling member N is "set" to and moved from the "set" position relative to said track.

40 It thus occurs that said safety members S S are at no time in position to interfere with the travel of a carriage on rails H H, such carriage at said time being movable thereunder, while at all times any of said 45 tracks formed by said rails R R, which are not continuous to the rails H H, are closed to the travel of a carriage thereon toward the switch by said members S S relating thereto resting thereon.

50 It will be observed, by reference to Figs. 2 and 4 that member F is provided with a semi-circular flange, f, at one end thereof, the upper face of said flange being in substantially the same horizontal plane as are 55 the upper faces of rails B, B, and H, H, and by reference to Fig. 1 it will be seen that rails B B abut against the circular portion of said flange, (but not attached thereto), and that rails H, H, abut against the ends 60 of said semi-circular flange.

It occurs that by placing wheels, which are respectively provided with a single flange, on said rails, with said flange on the outside thereof, (as indicated by lines Y, Y, 65 Fig. 1,) the rails H, H, may be turned in a

horizontal plane, a considerable angular distance without breaking the continuity of rails B, B, and the switch rails H, H.

I claim:

1. In a safety switch for a suspended two rail track a vertical member rigidly secured on the underside of a supporting member, and provided with a table and a base at the lower end thereof, a horizontally disposed member provided with a semi-circular annular flange fulcrumed on said table member in combination with rails secured to said base so that the ends thereof abut against the curved outside of said semi circular flange, and additional rails secured to said fulcrumed member so that the ends thereof abut against the ends of said semicircular flange, and traveling means to support the opposite ends of said last named rails. 70 75 80

2. In a switch for a suspended two rail track, a vertical member rigidly secured to the under side of a supporting member, and provided with a table and a base at the lower end thereof, a horizontally disposed member provided with a semicircular annular flange fulcrumed on said table member, rails secured to said base so that the ends thereof abut against the curved outside of said semicircular flange, and additional rails secured to said fulcrumed member so that the ends thereof 90 95 100 105 thereof abut against the ends of said semicircular flange, in combination with traveling means to support the opposite ends of said last named rails, said traveling means comprising a rigidly mounted track, a vertical member provided with a base, a pulley rotatably mounted on said vertical member adjacent to the upper end thereof and arranged to travel on said track, and means to secure said opposite ends to said base.

3. In a switch for a suspended two rail track, a vertical member, provided with a table and a base at the lower end thereof, a horizontally disposed member provided with a semicircular flange fulcrumed on said table member, rails secured to said base with the ends thereof arranged to abut against the curved outside of said semicircular flange, and additional rails secured to said fulcrumed member with the ends thereof arranged to abut against the ends of said semicircular flange, in combination with an additional vertical member provided with a base at the lower end thereof and a track adjacent to the upper end, and a traveling member, a pulley rotatably mounted on said traveling member and arranged to travel on said track, and means to secure the opposite ends of the rails secured to said fulcrumed member to said traveling member. 110 115 120 125

4. In a two rail suspended switch, rails, a pivoted member provided with a semicircular flange, and means to secure said rails to said pivoted member so as to respectively abut against the ends of said flange, in com- 130

bination with a rigidly secured member provided with a track and a traveling member provided with a base, a rotatably mounted pulley arranged to travel on said track and 5 means to secure said rails to said base.

5. In a two rail suspended switch, rails, a pivoted member provided with a semicircular flange, and means to secure said rails to said pivoted member so as to respectively 10 abut against the ends of said flange, in combination with a rigidly secured member provided with a track and a traveling member provided with a base, a rotatably mounted pulley arranged to travel on said track, 15 means to secure said rails to said base, means, comprising a longitudinally movable bolt, means to yieldingly maintain said bolt in an advanced position, and said rigidly secured member provided with recesses arranged to 20 co-act with said bolt.

6. In a two rail suspended switch, rails, a pivoted member provided with a semicircular flange, and means to secure said rails to said pivoted member so as to respectively 25 abut against the ends of said flange, in combination with a rigidly secured member provided with a track and a traveling member provided with a base, a rotatably mounted pulley arranged to travel on said track, and 30 means to secure said rails to said base, longitudinally movable bolts and pivotally mounted arms mounted on said rigidly secured member, said arms arranged to nor-

mally rest, at the free ends thereof, on adjacent rails, and a cam member mounted on 35 said traveling member and arranged to co-act with said bolt and arms to raise said arms on the contact of said cam and bolt.

7. In a two-rail suspended switch, rails, a pivoted member provided with a semi-circular flange, and means to secure said rails to said pivoted member so as to respectively 40 abut against the ends of said flange, in combination with a rigidly secured member provided with a track and a traveling member 45 provided with a base, a rotatably mounted pulley arranged to travel on said track, means to secure said rails to said base, means, comprising a longitudinally movable bolt, means to yieldingly maintain said bolt 50 in an advanced position, said rigidly secured member provided with recesses arranged to co-act with said bolt, longitudinally movable bolts and pivotally mounted arms mounted on said rigidly secured member, 55 said arms arranged to normally rest, at the free ends thereof, on adjacent rails, and a cam member mounted on said traveling member and arranged to co-act with said bolt and arms to raise said arms on the contact of said cam and bolt. 60
